UNITED STATES PATENT OFFICE.

KARL I. SMIDT, OF HOLTE, NEAR COPENHAGEN, DENMARK.

DEVICE FOR OILING THE INNER SURFACES OF THE COMBUSTION-CHAMBERS OF EXPLOSION-MOTORS.

1,245,466.

Specification of Letters Patent. Patented Sept. 17, 1918.

Application filed August 16, 1917. Serial No. 186,649.

To all whom it may concern:

Be it known that I, KARL I. SMIDT, engineer, of the village of Holte, near Copenhagen, Denmark, have invented certain new and useful Improvements in Devices for Oiling the Inner Surfaces of the Combustion-Chambers of Explosion-Motors, of which the following is a full, clear, and exact specification.

- 10 The present invention refers to devices for automatically oiling of the inner surfaces of the combustion chamber and at the same time supply of auxiliary air for the gas mixture.
- 15 The admixture of spirit with the burning substance as now generally used produces a very objectionable influence on the walls of the combustion chamber, which are attacked by the acetic acid released by the
- 20 burning of the spirit, which acid forms large furrows and grooves in the iron. By maintaining a fine coating of oil on the walls of the combustion chamber, the formation of the furrows and grooves and the
- 25 resulting injury thereto is avoided, and the present invention therefore aims at an automatic oiling of these surfaces by means of the oil saturated air from the crank chamber, which air is led to the main gas pipe where
- 30 it is mixed up with the gas, which at the same time becomes more explosive by the added auxiliary air.

The present invention may in practice be carried out by the apparatus shown on the drawing.

Figure 1 is an elevation of an explosion motor having the improvement applied; and

Fig. 2 is a vertical section through the valve.

- 40 On the drawing 1 is the motor cylinder, 2 the crank chamber and 5 the main gas pipe. From the crank chamber 2 leads a pipe 3 to a valve 4, which is open to the main gas pipe 5. In the valve is a changeable mouthpiece 7, a ball valve 6, and a spreader 8. The spreader which preferably
- 45 consists of a piece of wire netting as shown, serves to break up or spray the oil, so that it will be readily absorbed by the gas in the pipe 5.

The device acts in the following manner:

When the motor works the oil saturated air in the crank chamber will by the centrifugal force be hurled out against the walls of the chamber and a part will therefore be led through the pipe 3 and the mouthpiece 7 past the ball 6 to the main gas pipe 5, where it is mixed up with the gas, so that the oil will form a layer on the inner surfaces of the combustion chamber, 60 while the air will serve, in event of there being too much benzin in the gas mixture, to render the mixture more explosive.

As various quantities of air are necessary for the various types of motors, the valve 4 should be easily changeable and this is done by using various mouthpieces with larger or smaller canal diameter and by using larger or smaller respectively heavier or lighter balls 6.

It may therefore be possible in every single motor to adjust the device to the consumption of oil and auxiliary air necessary for it.

What I claim as new and desire to secure by Letters Patent is:

1. In a device of the character described, the combination with the crank chamber, and the gas supply pipe of the motor cylinder, of a pipe connecting the crank chamber 80 with the supply pipe, a ball valve in the pipe, and an adjustable mouth piece for regulating the passage of the oil saturated air through said pipe.

2. In a device of the character described, the combination with the crank chamber and the gas supply pipe of the motor cylinder, of a pipe connecting the crank chamber with the supply pipe, a valve in the pipe, a spreader in the pipe between the valve 90 and supply pipe, and means for regulating the passage of the oil saturated air through said pipe.

Signed by me at Copenhagen, Denmark, this 29th day of June, 1917.

KARL I. SMIDT.
